UNITED STATES PATENT OFFICE.

THAYER E. MELVIN, OF ALLEGHENY, PENNSYLVANIA.

TYPOGRAPHIC PAPER-PUNCH.

No. 813,907.

Specification of Letters Patent.

Patented Feb. 27, 1906.

Application filed July 11, 1905. Serial No. 269,266.

To all whom it may concern:

Be it known that I, THAYER E. MELVIN, a citizen of the United States of America, residing at Allegheny, in the county of Allegheny, 5 and State of Pennsylvania, have invented new and useful Improvements in Typographic Paper-Punches, of which the following is a specification.

This invention relates to a typographic paper-punch adapted to be locked in an ordinary chase and to be employed on a printing-press in connection with or independent of a type-form for perforating sheets of paper, the punch being formed on the ordinary 15 "point" system, so that it may be set up with type in a form to perforate the sheets as the impressions are made.

The object of the invention is to provide a simple, efficient, and reliable device of this 20 character whereby the operation of perforating sheets of paper, cardboard, or other materials may be cleanly and expeditiously performed and the cuttings collected in order to prevent the same from being scattered about 25 and clinging to the sheets or parts of the press.

The preferred embodiment of the invention is illustrated in the accompanying drawings, in which—

Figure 1 is a vertical longitudinal section 30 through the punch and receptacle. Fig. 2 is a cross-section through the punch on line 2 2 of Fig. 1. Fig. 3 is a bottom plan view of the punch and the adjacent portion of the receptacle, showing the connection at the base between 35 the same. Fig. 4 is a sectional view through the bed of the press, the platen, and the punch applied to a chase for use, showing the punch at the limit of its movement for perforating a sheet of paper. Fig. 5 is a detail view of the 40 impression-disk. Fig. 6 is a view similar to Fig. 1, showing a modification in the construction of the punch and receptacle; and Fig. 7 is a plan view showing the punch locked in a chase for use.

Referring now more particularly to the drawings, the numeral 1 designates a punch which comprises a block, preferably of rectangular form and cast or otherwise made on the point system, so that it may be set up 45 with ordinary type in a chase. The block is provided upon its outer face with a tapered punching projection 2 and a tapered passage 3, communicating therewith, which passage extends through the block to the base thereof, 50 at which point it communicates with a substantially U-shaped recess 4, opening through

one side of the block. At the latter-named side of the block an eduction-opening 5 is formed and communicates with the passage 3. The passage 3 receives the cuttings made 60 by the tubular punching projection 2 and permits the same to feed therefrom to the outlet-opening 5. The opening 5 communicates with a cuttings-receptacle 6, which may be formed of sheet metal or other suitable material. This receptacle 6 corresponds in width with the punch-block 1, but is of greater length and is preferably of oblong rectangular form. The outer end of the receptacle 6 is closed, while the inner end thereof is open 65 and is adapted to be closed by the punch-block. As shown, the said inner end of the receptacle is so constructed as to adapt the inner edges of its outer or front wall and its side wall to abut against the side of the block in 70 which the eduction-opening 5 is formed, while the base-wall of the receptacle is formed with a tongue or projection 7, corresponding in form to the recess 4 and adapted to fit within the same to hold the block and receptacle from independent movement when the two are locked in a chase for use. It will thus be observed that the cuttings received in the 75 passage 3 will feed therefrom through the eduction-opening 5 into the receptacle 6, in which they will be retained as long as the punch is in use, thus preventing the cuttings made by the punch from scattering and clinging to the sheets or parts of the press. When the punch is removed from the chase, the receptacle 6 may be readily detached therefrom and the cuttings discharged.

In the modified embodiment of the invention shown in Fig. 6 the punch-block 1^a is provided with a conducting-passage 3^a, which tapers or flares outwardly in length from the outer face of the block to the side thereof which abuts against the inlet end of the receptacle 6 and curves or extends from the outer face of the block through the side thereof to form a continuous passage to dispense with the use of the eduction-opening 5. The tubular punch 2^a in this form is provided with a threaded shank 2^b to fit into the outer threaded end of the passage 3^a. This construction permits of the ready removal of a dulled or worn-out punch projection and the substitution of a new one therefor.

Fig. 7 shows the application of the punch and its receptacle to an ordinary chase 8, 110 wherein it will be seen that the punch and receptacle are disposed longitudinally between

the pieces of furniture 9 and are clamped at their ends between quads 10, the furniture and quads being locked in the chase by the usual quoins 11. This view shows the application of the punch in its receptacle for perforating cardboard, paper, and other material which is not to be printed or prior or subsequent to the printing operation. It will also be apparent that as the punch and its receptacle are formed on the point system they may be set up in a form with ordinary printing-type, so as to be used for punching the paper or other material at the time the impression is made.

15 In the operation of the device it will of course be understood that the chase 8 containing the punch is locked to the bed 12 of the press in the usual way, while the sheet 13 to be perforated is applied to the platen 14. 20 In order to insure a clean cut of the punch through the sheet 13 and to properly back said sheet during the punching operation, an impression-disk 15 is preferably used. This disk, which may be made of lead or any other 25 suitable comparatively soft material, is provided with a central projection 16 to pass into the punch 2 or 2^a and is suitably secured to the tympan-sheet on the platen. When 30 the punch comes in contact with the sheet 13, the latter will be backed by the disk 15, thus allowing the punch to cut cleanly through the paper and the cutting to be forced by the projection 16 through the punch into the passage 3 or 3^a. By making the impression-disk 35 15 of lead or some other soft suitably relatively soft material the material to be punched will be efficiently backed, while undue wear upon the punch will be prevented. The projection 16 also coöperates with the punch to 40 form the perforation.

From the foregoing description, taken in connection with the accompanying drawings, the construction and mode of use of my improved punching or perforating attachment for printing-presses will be understood, 45 and it will be seen that it provides a punching device which is simple in construction, efficient in use, and may be employed in connection with a printing-form for perforating 50 the sheets at the time the impression is made and that substantial advantages are secured by the use of the receptacle 6 in order to pre-

vent the cuttings from being scattered and clinging to the paper or parts of the press.

The punch and its receptacle may of course 55 be made of varying sizes to meet different conditions of service.

Having thus described the invention, what is claimed as new is—

1. A punch comprising a block provided 60 with a perforating projection and a passage having a side outlet, and a receptacle having an open end adapted to be closed by the side of the block through which the outlet extends, said block and receptacle being coextensive 65 in width and adapted to be conjointly locked in a chase, and being independent of one another.

2. A perforating attachment for printing-presses comprising a block provided with a 70 punching projection and a passage communicating with said projection and having an outlet through one of the sides of the block, and a receptacle independent of the block and coextensive in width therewith, said receptacle having an open end adapted to bear 75 against and to be closed by the side of the block through which the outlet extends.

3. A perforating attachment for printing-presses comprising a block having a punching projection and a passage communicating therewith, said passage having an outlet 80 through one of the sides of the block, and a receptacle having an open end adapted to abut against and to be closed by the side of the 85 block through which the outlet extends, said block and receptacle having interengaging portions to hold them in assembled relation.

4. A punch comprising a block provided with a tubular punching projection, a passage 90 communicating therewith and provided with a side outlet, and a recess in the base of the block, in combination with a receptacle adapted to bear against the outlet side of the block and communicating with the passage 95 and provided with a tongue or projection to fit within said recess.

In testimony whereof I affix my signature in presence of two witnesses.

THAYER E. MELVIN.
